UNITED STATES PATENT OFFICE.

WALTER F. SCHULZ, OF YOUNGSTOWN, OHIO, ASSIGNOR TO TRUSCON STEEL COMPANY,
OF YOUNGSTOWN, OHIO, A CORPORATION OF MICHIGAN.

METAL CRATE.

Application filed January 4, 1926. Serial No. 79,153.

The present invention relates to metal crates for sheet material, particularly for paper.

Among the objects of the invention is a crate for such materials that will afford better protection than the packages heretofore used.

Another object is a crate of the kind indicated which will admit of handling with greater facility and yet hold a larger amount of the material than has been customary.

Still another object is to reduce the cost of packing such materials for shipment.

Heretofore, in shipping certain grades of paper in sheets it has been customary to pack the sheets in wooden boxes and because of the weight of the contents such boxes necessarily have to be carefully and strongly constructed and, if much paper is put into a single package, it is awkward and difficult to handle.

The present invention is intended to overcome these and other objections and consists broadly in a crate composed of stiffened metal plates between which a stack of the sheets may be placed and securely held by bolting the plates tightly together.

Reference should be made to the accompanying drawings, in which:-

- 30 Fig. 1 is a side elevation of the crate;
Fig. 2 is a plan view thereof;
Fig. 3 is an end elevation thereof;
Fig. 4 is a section on line 4—4 of Fig. 2;
Fig. 5 is a section on line 5—5 of Fig. 2;
35 Fig. 6 is an enlarged fragmentary detail showing the construction at one end of a rib; and
Fig. 7 is a section on line 7—7 of Fig. 6.

As indicated, the preferred form of the 40 crate consists of two sheet metal plates 10, provided with stiffening ribs 11 of sheet metal formed to trough-like shape, inverted on the plates and arranged in parallel relation as shown in Fig. 2. These ribs are 45 preferably welded along the flanged edges 12 to the plates 10 and are somewhat shorter than the width of the latter.

In addition to the ribs for stiffening the 50 plates laterally, a Z-bar 15 is placed along the longitudinal edges of the plates with its upper flange 16 resting on the ribs 11 and

its lower flange 17 resting on the margins of plates 10 with the web preferably welded to the ends of the ribs as at 15^a and the flanges to the parts with which they contact. Further, the edges of flanges 17 and plates 10 are preferably turned up as indicated at 18.

As already mentioned, the plates are secured together to form the crate by means 60 of rods 20, threaded at both ends for nuts 21 and the latter press against the flanges 17 of the Z-bars, preferably with an intervening washer or plate 22.

In order to permit removal and insertion 65 of the rods 20, it is preferred to notch the edges of plates 10 and flanges 17 as at 25 and to reinforce the Z-bars on either side of the notches with a corner rib 26, while holes 27 in the Z-bars facilitate handling by 70 allowing the use of hooks.

In the use of the device the sheets are, of course, clamped between plates 10 by means of the rods 20 and after removal of the contents, the plates may be packed in a comparatively small space and returned to the shipper if desired.

Having now described the preferred form of embodiment of the invention, it is to be understood that said invention is not to be 80 limited to the specific details herein described and shown but only by the scope of the claims which follow.

Claims:

1. A crate for sheet material consisting 85 of a pair of metal plates having stiffening ribs extending across one side and substantially smooth on the other and means for securing said plates together.
2. A crate for sheet material consisting 90 of a pair of metal plates forming a top and bottom of said crate, means for stiffening said plates crosswise and endwise, and means for drawing said plates together to thereby clamp between them the sheets of 95 material forming the load.
3. A crate for sheet material consisting 100 of a pair of metal plates forming a top and bottom of said crate, means for stiffening said plates crosswise and endwise, said endwise stiffening means being located along and reinforcing the longitudinal edges of

the plates, and means for drawing said plates together to thereby clamp between them the sheets of material forming the load.

4. A crate for sheet material including a plate, smooth on one side and provided with a plurality of hollow cross ribs on the other side, a Z-bar longitudinally arranged on said

plate with its upper flange secured to the top of said ribs and its lower flange secured to the edge of said plate, said latter flange and plate edge having openings for the passage of bolts or the like, and corner ribs in said Z-bar adjacent said openings. 10
